UNITED STATES PATENT OFFICE.

HENRY BLUGERMAN, OF TORONTO, ONTARIO, CANADA.

EXTENSION-BOX-COVER MACHINE.

Application filed October 8, 1925. Serial No. 61,233.

To all whom it may concern:

Be it known that I, HENRY BLUGERMAN, a subject of the King of Great Britain, and resident of the city of Toronto, county of 5 York, Province of Ontario, in the Dominion of Canada, have invented certain new and useful Improvements in Extension-Box-Cover Machines, as described in the following specification and illustrated in the accompanying drawings, that form part of the same.

The principal objects of the invention are to facilitate the work of assembling paper boxes having flanged or extension edges and 15 to increase the production and reduce the cost of manufacture to a minimum.

The principal features of the invention consist in the arrangement of adjustable stops upon a table adapted to hold the extension portion of the cover in position while the rim portion is centrally attached thereto.

In the drawings, Figure 1 is a side elevational view of a portion of a press showing the press ram and holding plate positioned 25 to receive the work.

Figure 2 is a perspective view of the holding plate, and Fig. 3 is an elevational view of a cover assembled.

Figure 4 is a perspective view of the two 30 portions of the cover arranged in a superposed position prior to being joined together.

In the present method of manufacturing certain classes of paper boxes, such as a confectionery box with an extension top and bottom, the cover and body portions are first stamped out in die presses and then formed in a forming machine and the corners are secured with glued strips, as shown in the upper portion of the illustration in 35 Figure 3.

A portion of the surface of a rectangular piece of paper board of greater area than the bottom surface of the formed cover or body portion, is partly covered with an adhesive and the formed portion is then placed upon the adhesively coated portion in a centralized position.

This hand method of placing the formed portion on the enlarged sheet of paper board 50 is very unsatisfactory, as it is very difficult to properly position the body portion on the larger paper board to leave the required even margin around the body portion. It is very necessary that these two portions be centered 55 with precision owing to the fact that the

paper covering for the two portions of the box are stamped out to exact dimensions to cover the portions and if any unevenness occurs the paper cover will overlap on one side and will not meet on the other, presenting a very unsightly box when finished.

To overcome this undesirable condition I provide the lower end of the plunger 1 of the press 2 with a rectangular box-former 3 of dimensions slightly greater than the inside dimensions of the box body portion 4.

Adjustably connected to the upper end of the central support 5 of the press is a rectangular plate 6 provided with a pair of parallel slots 7 arranged in central relation to one diameter of said plate and pairs of parallel slots 8 arranged in central relation to the other diameter and at each side of the slots 7.

Guide brackets 9 having upright ends are 75 adjustably secured to the plate by bolts extending into the slots 7 and 8, said bolts having wing nuts 10. The upper ends 11 of the brackets 9 are bevelled inwardly to guide the enlarged sheet 12 into place.

Suitable graduation marks are stamped in the surface of the plate 6 either side of the slots 7 and 8, and are preferably arranged to extend from the centre line of the plate and are spaced apart in half inch spacing 85 and numbered consecutively 1, 2, 3, 4, etc., which represent inch total lengths of cover, this greatly facilitating the accurate setting of the brackets.

When it is desired to make a box with the top and bottom projecting beyond the body portions the rectangular block 3 of proper dimensions is properly centered and securely fastened to the lower end of the plunger bar 1 and the brackets 9 are adjusted in the slots 90 7 and 8 to the graduations which will give the required area for accommodating the rectangular sheet 12 and locate it in central relation to the block. The operator then places a previously gummed rectangular sheet 12 between the brackets and at the same time places a cover or body portion on the block 3.

The press is then operated and the block 3 descends and places the body portion centrally on the gummed sheet 12 and presses the two portions securely together.

The plate 6 is supported on a spring ram 13 so that there is a flexible contact between the block and sheet and when the plunger 110

Minor changes may be made without departing from the spirit and scope of the invention as claimed.

What I claim as new is:

- 5 1. An improvement in saw mill head block cleaners comprising a conventional base plate, and a work feeding knee slide-
able along the upper face of the base plate; said improvement consisting of forming a
10 transverse diagonal groove in the base plate, said groove extending entirely across the upper face of the base plate, a scraper plate lying in said groove and twisted laterally at its upper end to extend diagonally across and in contact with the ad-
15 jacent face of said knee, and means ad-

justably and removably securing said plate in the groove.

2. A cleaner attachment for a conventional saw-mill head block, said attachment comprising a plate provided with longitudinally spaced elongated slots, the lower portion of said plate being relatively long and flat to provide an attaching portion to be connected to one flat side of said block, the upper end thereof being twisted laterally with its free upper edge cut diagonally whereby to extend diagonally across the top of said block.

In testimony whereof I affix my signature.

CHARLES D. BLAKE.
